UNITED STATES PATENT OFFICE.

EDWARD T. BURROWES, OF PORTLAND, MAINE.

DESIGN FOR A CURTAIN.

SPECIFICATION forming part of Design No. 29,954, dated January 3, 1899.

Application filed November 19, 1898. Serial No. 696,948. Term of patent 14 years.

To all whom it may concern:

Be it known that I, EDWARD T. BURROWES, a citizen of the United States, residing at Portland, in the county of Cumberland and State of Maine, have invented and produced a new and original Design for Curtains; and I do hereby declare the following to be a full, clear, and exact description of the same, reference being had to the accompanying drawing, forming a part thereof.

This invention relates to a new and original design for curtains; and it consists generally in the configuration and relative arrangement of parts hereinafter described, defined in the claim, and shown in the accompanying drawing.

The design is illustrated in elevation in the single figure shown in the drawing, it being understood that the reverse side is in all material and substantial respects the same as that shown.

In the drawing, A designates a window curtain or shade having on its lower edge the bottom portion or "leather" B. This bottom portion has at or near its central portion and slightly above the plane of the center the

transverse pocket C, which has at its ends the projections c.

At or near the lower edge of the part B is a relatively small pocket D, extending entirely across the part B and substantially of uniform diameter throughout. At the ends of the pocket D are projections d, extending a distance beyond the ends of the pocket and plane of the edges of the part B. The ends d 35 are finished so as to afford an attractive contrasting feature for the lower edge of the curtain.

The essential feature of the design is the curtain with the pockets and the associated 40 projections.

Having thus described the invention, what I claim as new, and desire to secure by Letters Patent, is—

The design for a curtain substantially as 45 shown and described.

In testimony whereof I affix my signature in presence of two witnesses.

EDWARD T. BURROWES.
